UNITED STATES PATENT OFFICE.

PATRICK J. CONNORS, OF GREENVILLE, PENNSYLVANIA, ASSIGNOR OF ONE-HALF TO
GEORGE KITCH, OF GREENVILLE, PENNSYLVANIA.

SAFETY DEVICE FOR WATER-GAGES.

1,101,255.

Specification of Letters Patent. Patented June 23, 1914.

Application filed July 31, 1913. Serial No. 782,234.

To all whom it may concern:

Be it known that I, PATRICK J. CONNORS, a citizen of the United States of America, residing at Greenville, in the county of 5 Mercer and State of Pennsylvania, have invented certain new and useful Improvements in Safety Devices for Water-Gages, of which the following is a specification, reference being had therein to the accompanying drawing.

This is an improvement in connection with a safety device for water gages disclosed in my pending application filed February 10, 1913, Serial Number 747,410. Besides having the same objects in view as disclosed in my pending application, the present invention aims to provide the slide of the protecting device with an outlet or drain opening, whereby broken glass, steam 20 or other matter that may accumulate within the device can be blown or discharged from the device, thereby reducing to a minimum the liability of the device being impaired by a burst water or steam gage, also the liability 25 of persons being injured in the vicinity of the same.

A further object of this invention is to provide an improvement of the above type that adds comparatively small expense, if 30 any, to the device disclosed in my pending application.

I attain the above and other objects by a mechanical construction that will be hereinafter specifically described and then 35 claimed, and reference will now be had to the drawing, wherein:

Figure 1 is a rear elevation of a safety device provided with my improvement, both of which are partly broken away, Fig. 2 is 40 a rear elevation of the detached slide embodying the improvement, Fig. 3 is a side elevation of the same, Fig. 4 is a front elevation of the slide, Fig. 5 is a plan of the same, and Fig. 6 is a cross sectional view of 45 the slide.

In order that those not conversant with my pending application may understand to a certain degree the application of the present improvement, there is illustrated in Fig.

50 1 a rear elevation of a casing 1 having connections 2 for a glass tube adapted to receive hot water and discharge steam or hot water at the upper end thereof. The casing has walls provided with transparent plates

and the rear wall has a dovetailed tapering seat 3 for a shutter or slide 4. The shutter or slide is dovetailed and tapered to fit in the seat 3 and the upper end of said slide has an outwardly extending handle or lip 5 whereby it can be easily moved into and out of engagement with the seat 3 of the casing 1. The slide 4, intermediate the ends thereof, is provided with an oblong opening 6 that is in communication with a sleeve coupling member or elbow 7, said member being formed integral with the rear or other side of the slide. The lower end of the member or elbow 7 is internally screw threaded, as at 8 to accommodate a pipe (not shown) should it be necessary to utilize such a conduit in connection with the safety device.

As disclosed in my pending application, the safety device has been designed to prevent firemen, engineers and others from being injured by flying glass or steam when the water gage bursts. The casing 1 constitutes a transparent inclosure and prevents flying glass or steam from injuring persons in proximity to the gage. To prevent the flying glass or steam from injuring the casing or subjecting it to undue stresses or strains, the slide 4 thereof, which has been used to permit of the casing 1 being easily cleaned, has the outlet or discharge opening 6. This opening not only relieves the pressure within the casing, but provides an outlet or discharge for flying glass, steam, hot water and in reality the contents of the casing when the gage bursts. In some instances it may not be necessary to use a pipe in connection with the member 7, as said member serves as a deflector for all matter discharged by the opening 6, the matter being deflected downwardly whereby it can do little, if any, harm.

It is thought that my improvement will be apparent in view of the disclosure of my pending application, and as in connection with this pending application it is to be understood that the structural elements are susceptible to such changes as fall within the scope of the appended claim.

What I claim is:

The combination with a safety device for water gages embodying a casing having one of the walls thereof provided with a dovetailed seat, of a dovetailed tapering slide

detachably mounted in the seat of said casting and having the upper end thereof provided with a handle, said slide having an opening formed therein, and a member carried by said slide and in communication with said opening and having provision for a conduit connection.

In testimony whereof I affix my signature in the presence of two witnesses.

PATRICK J. CONNORS.
